BRUSHLESS ERASER CLEANING MACHINE

Carl S. Coleman, Claremore, Okla.

Application July 28, 1950, Serial No. 176,497

4 Claims. (Cl. 15—305)

1

This invention relates to improvements in devices for cleaning blackboard erasers.

An object of this invention is to provide an improved brushless blackboard eraser cleaning machine which includes a support having a motor thereon, and means connected to the motor for performing the function of withdrawing powdered chalk, dust, etc. from the eraser and which has means connected thereto for rotating a cylinder in which the erasers are disposed, the dust and chalk extraction means being arranged axially of the cylinder, while air introducing pockets are arranged on the periphery of the cylinder to facilitate the withdrawing of air from the cylinder.

Ancillary objects and features of importance such as the saving of time and wear of the erasers will become apparent in following the description of the illustrated form of the invention.

In the drawings:

Figure 1 is a longitudinal sectional view of the device taken on line 4—4 of Figure 2 and in the direction of the arrows;

Figure 2 is a top view of the device in Figure 1;

Figure 3 is an end view of the device in Figure 2; and

Figure 4 is a transverse sectional view taken on line 4—4 of Figure 1 and in the direction of the arrows.

In carrying out this invention, there is provided a suitable stand or support, generally indicated at 10, which is made of structural framing members, as angle iron. The support is so arranged as to include a motor platform 12 with legs. There is a motor 14 disposed on a motor mount 16, said mount being carried by the platform 12. A pulley 15 is attached to the motor shaft 18 and has a belt 20 entrained therearound, this belt also being entrained around a pulley 22 which is fixed to the shaft 24. This shaft is mounted in bearings 25 and 26 which are disposed on a part 28 of the structural framing 10 and is employed to transmit movement to the pulley 30. This pulley is fixed to the shaft 24 and has a belt 32 entrained therearound, said belt also extending around a pulley 34 which is fixed to one end 36 of the cylinder, generally indicated at 38. Accordingly, upon operation of the motor 14, as controlled by a conventional switch, the cylinder 38 will be caused to rotate.

In order to mount the cylinder having the end wall 36 and an opposite end wall 40, there is a trunnion 42 fixed, for example, by the mounting plate 44, to the end wall 40 and there is

2

a hollow bearing 46 fixed by means of the mounting plate 48 to the wall 36. The trunnion 42 is disposed in a bearing 50 at the upper part of a vertical portion 52 of the framing 10, while the hollow shaft or bearing 46 is mounted in the conventional anti-friction bearing 54 which is disposed on another portion 56 of the structural framing support 10.

An air impeller serving as a suction motor or blower 60 is disposed on the platform 12 and has an exhaust hose 62 connected to the outlet 64 thereof. This outlet is formed in the case or fan housing 66 which is disposed around the impeller blade assembly 68. This blade assembly is connected to the shaft 18 by any suitable means, as by pinning or set screwing.

A longitudinal tube 70 is mounted axially in the cylinder 38 and is connected by means of the flared throat 74 to the fan housing 66 inlet. This tube is provided with longitudinal slots 72 for free air flow and each slot has a longitudinal lip 74 thereadjacent to act in the capacity of an air scoop. Accordingly, air drawn by the air impeller 60 is pulled through the outer open end 76 of the tube 70 and also through the slot 72 thereof.

A webbing, as a screen 80, is fixed in the cylinder 38 to prevent erasers from contacting the tube 70 but yet allow airflow therethrough. This webbing is held in place by a plurality of stay rods 78 which are secured to the ends of the cylinder.

The side wall or walls of the cylinder are made of sheet material, as at 84 (see Figure 4) and are provided with a number of longitudinal baffles 86 which extend from end to end in the cylinder 38. Any practical number of such baffles may be employed and the purpose of the baffles is to elevate the erasers and drop them on the stay rods 78 and thereby bounce the dust from the erasers. Longitudinal air slots 88 are arranged in the side wall 84 of the cylinder and there is an inwardly directed lip 90 adjacent each slot and an outwardly directed lip 92 on the other side thereof in order to serve as small air impellers for introduction of air into the cylinder for free circulation through the erasers in order to free them from powdered chalk, dust and other foreign matter.

There is a closure plate 96 arranged under the ribs 98 and 99 formed longitudinally at spaced longitudinal edges of the side wall 84 of the cylinder. A suitable latch 102 is operatively connected with the closure plate 96 and the side wall 40 of the device so that the closure plate is re-

leasably held in place by the cylinder. There is a trough 104 hinged at its inner end, as at 103, to a part of the structural makeup of the frame 10 and the trough serves the purpose of collecting and discharging the clean erasers.

In order to adjust the belts 32 and 20, the bearings 25 and 26 may be slid so as to move the shaft 24 laterally. These bearings are held on pillow blocks 103 and 110 and the pillow blocks are bolted, as at 112, to the element 28 of the structural framing in slots whereby the pillow blocks may be slid.

In operation, the closure panel or plate 96 is opened and the cylinder filled with erasers or a sufficient quantity of erasers placed therein. Then the closure panel 96 is replaced and the motor rendered operative. This causes suction in the cylinder. It also causes the cylinder to revolve. As it revolves, air is drawn through the slots 88 as aided by the lips 90 and 92, and also drawn through the slots 72. By this action, air is constantly drawn through the entire cylinder, thereby cleaning the erasers which are constantly agitated by striking the baffles 86 and the webbing 80.

Having described the invention, what is claimed as new is:

1. An eraser cleaning machine comprising a frame having a motor mounted thereon, a suction pump on said frame driven by the motor, a suction tube connected to the air inlet of said suction pump and having longitudinal slots therein, a cylindrical drum rotatably mounted on said frame, said suction tube extending axially through one end of said drum and terminating adjacent the other end thereof, said drum having air vents in the side wall thereof for admitting air to the drum, a plurality of spaced, circumferentially arranged stay rods extending axially within said drum and secured at their ends to the end of said drum, said stay rods being concentrically spaced around said suction tube, and a protective screen for said tube surrounding said stay rods, baffle plates extending radially inwardly from the side wall of said drum for elevating erasers disposed within the drum and dropping the same on the screen for impact against the stay rods.

2. An eraser cleaning machine comprising a frame having a motor mounted thereon, a suction pump on said frame driven by the motor, a suction tube connected to the air inlet of said suction pump and having longitudinal slots therein, a cylindrical drum rotatably mounted on said frame, said suction tube extending axially through one end of said drum and terminating adjacent the other end thereof, said drum having air vents in the side wall thereof for admitting air to the drum, a plurality of spaced, circumferentially arranged stay rods extending axially within said drum and secured at their

ends to the ends of said drum, said stay rods being concentrically spaced around said suction tube, and a protective screen for said tube surrounding said stay rods, baffle plates extending radially inwardly from the side wall of said drum for elevating erasers disposed within the drum and dropping the same on the screen for impact against the stay rods, and air scoops formed on the side wall of said drum adjacent said air vents for scooping air into the drum as the same is rotated.

3. An eraser cleaning machine comprising a frame having a motor mounted thereon, a suction pump on said frame driven by the motor, a suction tube connected to the air inlet of said suction pump and having longitudinal slots therein, a cylindrical drum rotatably mounted on said frame, said suction tube extending axially through one end of said drum and terminating adjacent the other end thereof, said drum having air vents in the side wall thereof for admitting air to the drum, a plurality of spaced, circumferentially arranged stay rods extending axially within said drum and secured at their ends to the ends of said drum, said stay rods being concentrically spaced around said suction tube, and a protective screen for said tube surrounding said stay rods, baffle plates extending radially inwardly from the side wall of said drum for elevating erasers disposed within the drum and dropping the same on the screen for impact against the stay rods, said elongated slots in said suction tube extending substantially the entire length of said drum.

4. An eraser cleaning machine comprising a frame, a drum rotatably mounted on said frame, a suction pump carried by said frame, a suction tube connected to the air inlet of said pump and extending axially through one end of said drum and terminating adjacent the other end of said drum, the portion of said tube disposed within said drum having elongated slots therein extending substantially the length of the portion, a plurality of stay rods mounted within said drum arranged in concentrically surrounding relation to said tube and a protective screen for said tube surrounding said stay rods, baffle means on the inner surface of the side wall of said drum for elevating erasers as the drum is rotated, said drum side wall further having air vents therein for drawing air into the drum and through the suction tube and driving means for said drum.
